Filed Sept. 29, 1959, Ser. No. 57,723

Term of patent 14 years

(Cl. D54—13)

Fig. 3

Fig. 4

Fig. 5

Fig. 1 is a perspective view of an air jig embodying my new design;

Fig. 2 is a top plan view;

Fig. 3 is a right side elevational view;

Fig. 4 is a left side elevational view;

Fig. 5 is a front elevational view, and

Fig. 6 is a fragmentary rear elevational view of the air jig.

The dominant features of my design reside in the portions shown in full lines. Portions of the jig are broken away in Figs. 3, 4, 5 and 6 for convenience of illustration only.

I claim:

The ornamental design for an air jig, substantially as shown and described.
